UNITED STATES PATENT OFFICE.

GUSTAV A. VASEL, OF PHILADELPHIA, PENNSYLVANIA.

INK-GRINDER-ADJUSTING ATTACHMENT.

Application filed November 12, 1926. Serial No. 147,879.

My invention relates to adjusting mechanism for ink grinders, and more particularly to an attachment for adjusting roller mills.

5 Under the present method of adjusting the front roll of an ink grinding mill, each of the ends is moved independently from the other, thus consuming considerable time in making the proper adjustment in order to 10 secure the required fineness of the product.

The principal object of my invention is to so connect the adjusting means that all 15 adjustments may be made from one end of the mill.

15 A further object is to so place the controls that the operator can simultaneously reach one with either hand.

These objects, and other advantageous 20 ends which will be described hereinafter, I attain in the following manner, reference 25 being had to the accompanying drawings in which

Figure 1 is a plan view of an ink grinding mill on which my attachment has been installed,

Figure 2 is a front elevation of the mill shown in Figure 1,

Figure 3 is a view taken on line 3—3 of Figure 2, some of the parts being omitted 30 for the sake of simplicity,

Figure 4 is a fragmentary front view, some of the parts being omitted for the sake of simplicity,

Figure 5 is a cross sectional view taken on 35 line 5—5 of Figure 4, and

Figure 6 is a cross sectional view taken on line 6—6 of Figure 4,

Figures 3, 4, 5 and 6 are drawn to a larger scale than Figures 1 and 2.

40 Referring to the drawings, 7 indicates the frame of a roller mill, 8 a bracket attached to one end of the frame, 9, 10 and 11 the grinding rolls which are actuated by means of belts engaging pulleys 12 and transmitting 45 rotation through the train of gears 13, and 14 represents the discharge apron. The above enumerated parts are the principal elements of a well known roller type grinding mill and will not be further described 50 as they form no part of my invention.

55 15 and 15^a represent the adjustable bearings in which the front roll is mounted. Engaging the front side of the bearing 15 through swivel connection 14^a is a screw 16, threaded through a block 17 secured to the

frame 7, and having a helical gear 18 mounted near its center. The screw is mounted in a bearing 19 which is secured to the frame of the mill in any suitable manner. A screw 20, having a helical gear 18^a mounted thereon and which is threaded through a block 17^a secured to the frame 7, is bored throughout its length and has a secondary screw 21 rotatably mounted therein with its inner end engaging bearing 15^a 60 through swivel connection 14^b. An enlarged threaded portion 22, of the screw 21, engages threads in a counter-bored portion 23 of the screw 20. The screw 20 is mounted in a bearing 24 secured to the frame of the 70 roller mill in any suitable manner. Immediately below the gears 18 and 18^a, on the screws 16 and 20, is mounted a longitudinal shaft 25 having helical gears 26 and 26^a rigidly secured thereto and meshing with 75 the gears 18 and 18^a respectively. The shaft is held against longitudinal movement by collars 27 and 27^a secured on either side of the bearings 19 and 24. A hand-wheel 28 is secured on one end of the shaft 25 and another hand-wheel 29 is secured on the 80 screw 21.

By turning hand-wheel 28, attached to shaft 25, the screws 16 and 20 will be rotated by the action of the helical gears 18 and 26, attached to the screws and shaft respectively. As the screws are threaded through the blocks 7 and 7^a attached to the mill frame with the inner end of screw 16 engaging roll bearing 15 and the end of secondary screw 21 engaging roll bearing 15^a, pressure between the rolls may be increased or decreased as desired. When it is discovered that the rolls are not bearing evenly throughout their lengths, adjustment is 90 made by turning hand-wheel 29 attached to screw 21. The hand-wheels are located adjacent one another so that the operator may grasp one in either hand and instantly make accurate adjustments.

100 While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

105 Having thus described my invention, what 110

I claim as new and desire to secure by Letters Patent is:—

1. In combination with a color grinding machine having parallel rolls, one of said rolls being mounted on adjustable bearings, means at either end of said roll operable responsive to a single control for simultaneously moving said bearings to adjust said roll with respect to the other rolls, and means associated with one of said adjustable bearings and passing through said first means thereat adapted to adjust said bearing independently of the other of said bearings.
2. In combination with a color grinding machine having parallel rolls, one of said rolls being mounted on adjustable bearings, a threaded member at either end of said roll passing through a stationary block of the machine and swiveled to said bearings, a shaft having means thereon and a control for operating said means to adjust said members simultaneously, and threaded means passing through one of said blocks and the member associated therewith for
3. In combination with a color grinding machine, parallel rolls, one of said rolls being mounted on adjustable bearings, a threaded inner member at each end of said roll passing through individual blocks thereat, an outer member removably secured to each of said inner members, a gear on each of said outer members, a shaft having gears thereon, whereby upon the actuation of a single control, said shaft is adapted to actuate said gears and members, one of said inner members being swiveled to one of said adjustable bearings, a threaded rod passing through the other inner member and swiveled to the other adjustable bearing, said rod being adapted to adjust said bearing independently of the other bearing, both said bearings being adapted to be adjusted simultaneously and equally by a movement of the shaft.

In testimony whereof I have signed my name to this specification.

GUSTAV A. VASEL.
